W. HEUSSER

TELEPHONE RECEIVER

Filed April 14, 1923

UNITED STATES PATENT OFFICE.

WILFRID HEUSSER, OF SALT LAKE CITY, UTAH.

TELEPHONE RECEIVER.

Application filed April 14, 1923. Serial No. 632,080.

This invention relates to telephone receivers, and other sound reproducing devices, but more especially to those which are applicable to radio telephony.

5 The principal objects of this invention are to provide an instrument which shall:

First. Have extreme sensitivity.

Second. Be rugged and staunch in construction.

10 Third. Have few parts, and therefore great simplicity.

Fourth. Be reliable and durable in service.

Fifth. Be compact in form.

15 Sixth. Be designed with special regard for quantity production in manufacturing, so that the instruments may be sold at moderate prices.

This invention is applicable to telephone receivers of various kinds, but for convenience, its specific application to receivers having tensioned diaphragms, is shown and described herein.

In the drawing,

20 Fig. 1 represents a section through a receiver embodying this invention, taken partly on line 1 and partly on line 1^a in Fig. 4;

Fig. 2, section on line 2, Fig. 4;

25 Fig. 3, an elevation in the direction of the arrow 3 in Fig. 4, the casing in the foreground being omitted, and parts shown in section on line 3^a;

Fig. 4, a front elevation partly in section 30 on line 4, Fig. 2;

Fig. 5, an enlargement of the portion enclosed by the broken line 5, indicated in Fig. 4, coil omitted;

35 Figs. 6 and 7, sections taken respectively on lines 6 and 7 in Fig. 5;

Fig. 8, a fragmentary elevation in the direction of arrow 8 in Fig. 7;

40 Fig. 9, a central cross-section through an instrument having a double actuating mechanism;

Figs. 10 and 11, enlarged details showing method of suspending one end of the armature;

45 Fig. 12, an enlarged detail showing method of suspending the armature in an instrument having a double actuating mechanism;

Figs. 13 and 14, diagrams of the magnetic circuits in a single instrument; and

50 Figs. 15 and 16, the same, in a double instrument.

Referring to the drawing, 20 indicates a permanent magnet having what I choose to call a "box" or C form, the poles 21 and 24 being located in the jaws of the C, directly opposed to each other, and slightly spaced apart to form an air gap, as shown in Figs. 2 and 3.

The magnet 20 may be permanently fastened to the foundation plate 25, by any suitable means, for instance, rivets 26. The foundation plate may be countersunk to receive the diaphragm 27. A second diaphragm 28 may be placed directly opposite the first diaphragm, and be supported in the holding plate 29. The holding plate may be spaced apart from the foundation plate 25, by means of the shouldered portions of pins 30, which also have the threaded ends 31 and 32. The ends 31 may be screwed into the foundation plate while the holding plate may be slipped over the opposite ends 32, against the shouldered portions of the pins, as shown in Fig. 3.

Within the magnet 20 may be the coils 34, made of fine wire and wound upon the spool 35 in the usual manner. This spool may have an elongated form as shown in Fig. 1, and have a core space in the form of the elongated slot at 36. In the back part of the magnet may be formed the V-shaped groove 37, directly opposite the opening between the poles 21 and 24. The elongated coil 34 may be clamped between the legs of the magnet 20 by the screws 38 (Fig. 1) the latter being intended primarily, however, for adjusting the air gap between the poles or jaws of the permanent magnet.

The elongated slot should be in central alignment with the gap and with the groove 37. An armature 40, made of suitable material, such as silicon steel or soft iron, and having the knife edges 41, is placed to rock in the V-shaped groove 37, preferably in the neutral part of the magnet 20, as clearly shown in Fig. 6. Between the knife edges 41 (Fig. 5) the armature 40 is provided with a lug 42, in which may be the eye portion 43, countersunk from both sides of the armature plate to form a circular knife edge.

105 The knife edges of the armature may be held in the contact with the bottom of the V-groove, by means of a link having the hook portions 45 and 46, one hook extending through the eye 43, and the other engaging a piece of spring wire 47 under tension, which acts in the direction of the arrow 51, (Fig.

7). The ends of the spring 47 may rest in grooves 48 in the frame of the permanent magnet 20. The lug 42 is accommodated by the hole 49 in the magnet frame, and this hole may be countersunk as shown at 50, to provide clearance for the free movement of the contiguous parts holding the armature. The armature lies in the neutral zone of the magnet, and magnetically contacts the neutral portion of the permanent magnet.

Obviously, the armature 40, rocking on the knife edges 41, is free to move to either side in the directions indicated by the arrows (Fig. 6) with a minimum of friction at its bearing. The other end of the armature 40 is provided with the integrally formed neck 52 and head 61 (Fig. 4). Hangers 53 and 54, arranged for pulling in opposite directions, as clearly shown in Fig. 10, and having respectively the knife edges 55 and 56, which bear on opposite sides of the neck 52 of the armature, eliminate entirely, the possibility of any lost motion in the connection of the hangers to the armature. The hangers 53 and 54 are engaged by hooks 56 forming parts of the adjusting bolts 57. The latter project through the diaphragms 27 and 28, and are fitted with the threaded nuts 58 for tensioning the diaphragms 30 against each other, as shown in Figs. 2, 10 and 11.

The entire structure as just described, is enclosed by the casing 62, into which are also fitted the back plate 63, and the ear-piece 64, both of which are preferably made of some electric insulating material, such as bakelite. The back plate 63 is provided with holes to pass over the threaded ends 32 of the pins 30, and is secured by the nuts 65. The ear-piece 64 is provided with holes to pass over the threaded ends 31 of the pins 30, and is secured by the nuts 67. Leads (not shown) and terminals (not shown) in any well known forms, may be provided for conducting an electric current to the coil 34.

When a current is flowing through the coil, the armature becomes electro-magnetic, with a certain polarity, and when the current through the coil is reversed, the polarity of the armature is, of course, also reversed.

To describe the action of this instrument in use, we will suppose an electric current to be passing through the coil, in a direction to produce the polarity in the armature indicated by the diagram in Fig. 13, where the south pole of the armature is in the gap between the poles of the permanent magnet. Such a polarity in the armature, would cause the S pole of the armature to be attracted by the N pole of the permanent magnet, and to be repelled by the S pole of the permanent magnet. Now, if the electric current in the coil is reversed, the polarity of the armature is also reversed, so the end of

the armature in the gap would now become the N pole of the armature. In this case, the end of the armature in the gap between the poles of the permanent magnet, would be attracted to the S pole thereof, and repelled by the N pole.

By alternate reversals of the electric current flowing through the coil, the polarity of the armature is correspondingly reversed, thereby causing its free end to be pulled back and forth while rocking on its knife edge bearing.

The arrows in the diagrams indicate the directions of the magnetic fluxes in the various circuits.

The oscillations of the armature, transmitted through the hangers 53 and 54, influence the diaphragms 27 and 28 accordingly. Obviously, any sounds at the sending end of a telephone electric circuit, will produce undulations in the current flowing through the coil 34, and cause vibrations of the armature 40, in exact harmony therewith. These vibrations, being transmitted to the diaphragms, reproduce the sounds which control the sending end of the circuit.

In the double instrument, as illustrated in Fig. 9, there are two magnets, 70 and 71; two coils, 72 and 73; and two armatures 74 and 75; all these being similar to the corresponding parts in the single instrument.

The armatures 74 and 75 have their free ends superposed as shown in detail in Fig. 12, the lugs 76 and 77 being slightly offset, and the lug 76 bearing on the conical point 100 portion 78, forming part of the lug 77.

The circular knife edge 79 of the hanger 80, bears on the neck of the lug 76, while the circular knife edge 81 of the hanger 82, bears on the neck of the lug 77. The combined motions of the armatures 74 and 75 are transmitted to the diaphragms 83 and 84 in the same manner as described for the single instrument.

The diagrams in Figs. 15 and 16 represent the magnetic fluxes and the effects on the armatures, in a manner corresponding to the diagrams in Figs. 13 and 14, of the single instruments.

It is to be noted that the knife edges of the armatures are in magnetic contact with the permanent magnet, so as not to impede the free passage of the magnetic fluxes.

In emphasizing what has been stated, it will be clear that a tensionable element, tensioned to be normally under a stress, which may be defined as an "initial stress" is more susceptible to slight stress increments imposed thereon, than is the same tensionable element susceptible to a stress equal to the increment stress, when this is imposed on the tensionable element in the unstressed condition thereof. In the case of two mutually opposed diaphragms connected to each other as explained, either one may be

regarded as the tensionable element for exerting the initial stress on the other, in balanced relation thereto.

The stressing of the diaphragms, and notably so, the mutual stressing of mutually opposed, identically similar diaphragms, accounts for the remarkable clearness of sound reproduction, possible by the use of this invention.

10 It will be observed in the drawing, that the motive power is applied directly, close to the point of use, and that its force is transmitted in very nearly right lines, so that there is practically no loss of power, 15 as there would be in transmitting motion through levers, or other power-consuming elements, or from point to point along directional elements forming excessive diagonal components.

20 The armature, from the center of oscillation to the center of polar application of power, may be made of considerable length, comparatively, so that the angle of oscillation shall be small, and consequently, the 25 variation of the angle between the plane of the armature and the line of action of the connection between the diaphragms, from a right angle, will at all times be negligible. Also, because the connection between the 30 armature and the diaphragm is closely adjacent the poles of the permanent magnet, and remote from the center of oscillation, the bending of the armature in action will be negligible.

35 While one diaphragm is under a positive pulling stress from the armature, the initial tension of the other diaphragm remains effective on the armature, allowing it (the said other diaphragm) to follow promptly, the movement of the armature. When the motion of the armature is reversed, the actions 40 of the diaphragms are also reversed.

The initial tension between the diaphragms should be so adjusted that the action of each diaphragm in following the motion of the armature, shall hold taut the respective hanger. This establishes a condition where the motions of the diaphragms are substantially simultaneous and identical.

45 While for convenience, specific embodiments of this invention are herein shown and described, it should be clearly understood that the preferred details thereof, may, or may not, be as shown or described, and further, that the preferred details may be varied from time to time, depending upon the circumstances and conditions governing, and governed by, the development of the invention and the arts to which it is incident.

To the skilled inquirer, therefore, that which is an essential and characteristic part of this invention, is readily discernible from

the claims in which is embraced a broad generalization of its spirit. 65

Having described my invention fully, what I claim is:

1. A sound-emitting element, an oscillating armature arranged to actuate said element, a knife-edge bearing for said armature, and a tensioned spring for holding the armature against the said bearing, said spring comprising a wire acting in the plane of the armature. 70

2. A sound-emitting element, an oscillating armature having a knife-edge, said armature arranged for imparting motion to said element, a bearing for said knife-edge and a tensioned spring for holding said armature against said bearing said spring acting in 80 the plane of the armature.

3. A telephone receiver comprising two diaphragms disposed in opposing relation to each other, a tie joining the diaphragms to each other, an oscillating member having one 85 end thereof connected to the said tie, a knife-edge bearing at the center of oscillation, a spring exerting pressure on said bearing, and means for vibrating the said oscillating member through the influence of an 90 electric current.

4. A telephone receiver comprising a permanent magnet, an electro-magnetic armature having a tensionable knife-edge bearing operably mounted between the poles of said permanent magnet, means for energizing said armature, two diaphragms mounted in 95 mutually opposed relation, a tie joining said diaphragms to each other, and means for operably connecting said armature to said 100 tie.

5. An armature having a knife-edge, a permanent magnet having a bearing for said knife-edge, a spring arranged to hold the knife-edge against the bearing, a diaphragm 105 connected to said armature, and a coil for actuating the armature.

6. A permanent magnet having a C-form, an armature arranged to vibrate between the jaws thereof, a bearing for the armature located opposite the jaws, a spring arranged for tensionably holding the armature against the bearing, a diaphragm connected to the armature, and a coil for actuating said armature. 110

7. A permanent magnet having a C-form, an armature arranged to vibrate between the jaws thereof, a grooved bearing inside the magnet for said armature, opposite the said jaws; a spring wire tensioned against the outside of the magnet opposite the armature, and a link connecting the spring wire to the armature. 120

In testimony whereof, I sign my name hereto.

WILFRID HEUSSER.
